DESIGN FOR A JAR FOR COSMETICS

Jean E. Vivaudou and Henry G. Lubin, New York, N. Y.

Application May 14, 1942, Serial No. 106,898

Term of patent 7 years

To all whom it may concern:

Be it known that we, Jean E. Vivaudou and Henry G. Lubin, subject of Great Britain and citizen of the United States, respectively, both residing at New York city, in the county of New York and State of New York, have invented a new, original, and ornamental Design for a Jar for Cosmetics, of which the following is a specification, reference being had to the accompanying drawing, forming a part thereof.

In the drawing:

Fig. 1 is a perspective view of a jar for cosmetics, showing our new design.

Fig. 2 is an enlarged side elevational view of the same;

Fig. 3 is a top plan view of the same.

The design on the opposite side of Fig. 2 is similar to that shown in Fig. 2.

We claim:

The ornamental design for a jar for cosmetics, as shown and described.

JEAN E. VIVAUDOU.
HENRY G. LUBIN.
